Inventor:
Frederick P. Marx,
by Ripper & Kingsland, his Attorneys.

UNITED STATES PATENT OFFICE.

FREDERICK P. MARX, OF ST. LOUIS, MISSOURI.

SHANK STIFFENER.

Application filed October 2, 1922. Serial No. 591,820.

To all whom it may concern:

Be it known that I, FREDERICK P. MARX, a citizen of the United States, residing at St. Louis, Missouri, have invented a new and useful Shank Stiffener, of which the following is a specification.

This invention relates to shank stiffeners.

An object of the invention is to provide an improved shank stiffener adapted to be built into a shoe sole and which consists essentially of a rear section that extends from a point rearwardly of the vertical axis of the shoe heel to a point beneath the arch of the foot in front of the shoe heel, and a front section pivotally united with the rear section and having means for limiting the pivotal and longitudinal movement thereof.

Other objects will appear from the following description, reference being made to the drawing in which

Fig. 1 is a broken view of a shoe sole showing one embodiment of the invention therein.

Fig. 2 is a longitudinal sectional view.

Fig. 3 is a broken view of the shoe sole showing another satisfactory embodiment of the invention therein.

Fig. 4 is a longitudinal sectional view of the device shown in Fig. 3.

The invention as shown comprises a support 1 in the form of a metallic plate built into the shank and heel portion of the shoe and extending rearwardly to a point near the rear wall of the heel. This construction provides a relatively long portion of the part 1 rearwardly from the breast wall of the heel, so that the rear portion of the part 1 of the shank stiffener is below the ball of the heel of the wearer of the shoe. Thus the principle of greater weight of the wearer of the shoe is upon the inner sole of the shoe above the rear end of the part 1 of the shank stiffener when the wearer is standing. The part 1 of the shank stiffener extends forwardly under the arch of the foot and is there pivotally united with the front section 2 of the shank stiffener. The pivotal connection of the parts 1 and 2 permits proper vertical pivotal action and slight lateral action of said parts in order to conform to the needs of the wearer in walking.

In the construction shown in Figs. 1 and 2 the forward end of the rear section 1 of the shank stiffener is formed with a hole 3 which receives a rolled or knuckle portion 4 on the rear end of the forward portion 2. A pin

5 within the rolled or knuckle portion 4 engages in a depressed portion 6 of the arch member 1 and thus forms a pivotal connection permitting vertical, lateral and longitudinal movement of the part 2 relative to the part 1 and at the same time retains said parts in proper connection for best results. This is because the hole 3 is large enough to permit such movement by the knuckle 4 and because the depression 6 is large enough to permit such movement by the pin 5. This allows the forward end of the rear part 1 to raise according to the pitch of the heel. The part 2 of the shank stiffener extends under the forward end of the part 1 so that upward swinging movement of the part 2 is limited by the overrunning portion of the part 1 and the pivot pin 5.

In the embodiment shown in Figs. 3 and 4 the part 2 extends a slight distance under the forward end of the part 1 and has a pair of ears 7 extending through the hole 3 bent to seat in the depressions 8 at the sides of the hole 3. This connection also permits vertical and lateral pivotal movement of the part 2 relative to the part 1 of the shank stiffener and also slight longitudinal movement and prevents said parts from becoming detached. If desired the part 2 may be further secured to the shoe sole by tacks 9.

Obviously the invention may be varied otherwise than as described without departure from the nature and principle thereof.

I do not restrict myself unessentially, but what I claim and desire to secure by Letters Patent is:—

1. In a shoe, a shank stiffener comprising a rear section having about half of its length over the heel of the shoe and behind the breast wall of the shoe, a front section extending under the forward end of the rear section, and a pivot device uniting said two sections and limiting relative longitudinal movement thereof and permitting vertical and lateral pivotal movement.

2. In a shoe, a shank stiffener comprising a metallic member extending above the heel of the shoe to a point near the rear wall of the shoe heel and extending forwardly into the arch of the shoe sole, a forward metallic member extending from a point under the forward end of the first member, and means pivotally uniting said two members and limiting their longitudinal movement and per-

mitting vertical and lateral pivotal movement thereof.

3. In a shoe, a shank stiffener comprising a metallic member extending above the heel 5 of the shoe to a point near the rear wall of the shoe heel and extending forwardly into the arch of the shoe sole, a forward metallic member extending from a point under the forward end of the first member, and means 10 pivotally uniting said two members and limiting both their longitudinal and lateral movements.

4. A shank stiffener, comprising a rear section having a hole in its forward end, a 15 front section extending under the forward

end of the rear section and having a portion extending upwardly through the hole in the rear section, and means in connection with said two sections limiting relative longitudinal movement thereof and permitting lateral and vertical pivotal movements thereof. 20

5. A shank stiffener, comprising a rear section having a hole in its forward end, a front section extending under the forward end of the rear section and having a portion 25 extending upwardly through the hole in the rear section, and means in connection with said two sections limiting both their longitudinal and lateral movements.

FREDERICK P. MARX.
